UNITED STATES PATENT OFFICE.

MAX E. CRANDALL, OF KINGFISHER, OKLAHOMA, ASSIGNOR OF ONE-HALF TO L. J. CONN, OF KINGFISHER, OKLAHOMA.

WRENCH.

1,118,532.

Specification of Letters Patent Patented Nov. 24, 1914.

Application filed June 10, 1913. Serial No. 772,863.

To all whom it may concern:

Be it known that I, MAX E. CRANDALL, citizen of the United States, residing at Kingfisher, in the county of Kingfisher and 5 State of Oklahoma, have invented certain new and useful Improvements in Wrenches, of which the following is a specification.

This invention relates to wrenches and has as its object to provide a wrench which 10 will automatically adapt itself to the nut or pipe to be turned and which will firmly grip the nut or pipe as pressure is exerted against the handle.

It is another aim of the invention to so 15 construct the wrench that the movable jaw thereof may be readily adjusted along the fixed jaw and its shank by the thumb of the hand grasping the wrench handle.

The invention also aims to provide a support 20 for the movable jaw which, while it will be firmly and securely held in adjusted position, may be readily adjusted by the thumb as above stated.

Another feature of the invention resides 25 in so constructing the wrench that the working faces of the fixed and movable jaws will be at all times parallel regardless of the size or diameter of the pipe or nut gripped between them.

30 In the accompanying drawings: Figure 1 is a perspective view of the wrench embodying the present invention; Fig. 2 is a view partly in side elevation and partly in section illustrating the wrench applied to a pipe to be turned; Fig. 3 is a group perspective view illustrating the support or mount for the movable jaw of the wrench.

Corresponding and like parts are referred 40 to in the following description and indicated in all the views of the accompanying drawings by the same reference characters.

In the drawings, the handle of the wrench is indicated by the numeral 1 and beyond its grip portion it is formed into a shank 2 and fixed jaw 3. It is preferable that the shank and jaw be of substantially the same dimensions in order that the mount for the movable jaw may have great latitude of adjustment thereon, in a manner that will be 45 presently explained. The fixed jaw 3 is provided with a serrated working face 4 and it will be observed that the teeth of this face extend transversely thereof and are inclined at an angle from the plane of the

face in the direction of the extremity of the 55 jaw. For a purpose which will be presently explained, the rear face of the jaw 3 and shank 2 is formed with a number of transversely extending grooves or seats 5 substantially semi-circular in contour. 60

The support for the movable jaw is preferably formed from a blank of heavy sheet metal and includes spaced cheek plates 6 and a connecting portion 7 which extends between and connects the rear ends of the 65 said plates. The plates adjacent their rear ends are offset rearwardly, as at 8, so as to fit against the sides of the shank 2 and jaw 3, it being observed that the plates lie upon opposite sides of said jaw and its shank. 70 The offset portions 8 of the cheek plates are provided upon their forward edges with inwardly projecting fingers 9, the ends of which register as shown in Fig. 3. In addition to the connecting portion 7 the cheek 75 plates are connected by transversely extending pins 10 of which there are two, these pins being so spaced that they will engage in spaced ones of the seats 5 in the manner shown in Figs. 1 and 2. In order to hold 80 the support in position with the pins engaging in the seats, as stated, there is provided a leaf-spring 11 which has one end bent substantially at right angles as at 12 and its intermediate portion bowed, as at 85 13, the other end of the spring being acutely bent, as at 14, so as to coöperate with the teeth 4 of the fixed jaw.

In assembling the spring of the support, it is inserted beneath the fingers 9 and its 90 end 12 is engaged behind the connecting portion 7, it being observed that the adjacent end of the bowed portion 13 forms a shoulder 15 which abuts against the edges of the fingers 9 and serves to prevent dis- 95 placement of the spring and disengagement of its end 12 from the connecting portion 7. By referring to Fig. 2 of the drawings, it will be seen that while the spring normally holds both of the pins 10 engaged in the 100 seats 5 and holds the connecting portion 7 spaced from the forward face of the shank 2 and jaw 3, pressure may be exerted against the spring and against the connecting portion 7 in the direction of the shank 2 so as 105 to disengage the pins from the seats, whereby to permit of the sliding of the support along the shank and jaw.

The movable jaw is indicated by the reference numeral 16 and it is provided with a toothed or serrated working face 17, the teeth projecting at an angle from the plane 5 of the said face and in direct opposition to the teeth 14 of the fixed jaw. The movable jaw is supported by two pairs of parallel links 18, a pair being located at each side of the wrench and the links of each pair being 10 pivotally connected with the adjacent ends of the pins 10. The outer or forward ends of the links are pivoted to the ends of pins 19 which are fitted through the movable jaw 15. As stated above the links are parallel 15 and as a consequence when they are swung so as to move the jaw 16 toward and away from the jaw 3, the jaws will be maintained in parallel relation. It will be apparent that the support for the movable jaw may be adjusted along the shank 2 and fixed jaw 3 so 20 as to adapt the jaws to grip nuts and pipes of various diameters. For if the lower one of the pins 10 in Fig. 2 of the drawings, is engaged in the lower one of the seats 5 in 25 said figure, and the movable jaw is moved into engagement against the face of the fixed jaw 3, the extremities of the jaws will register and consequently the maximum bearing 30 surface is provided and the wrench is adapted for use in gripping nuts and pipes of small diameter. When the wrench is to be employed in gripping nuts and pipes of large diameter, however, the support is slid upon the shank 2 until the pins 10 engage 35 in the upper ones of the seats 6. It will, of course, be understood that when the wrench is held approximately horizontal with the movable jaw uppermost and the fixed jaw 3 is disposed against the under side of a 40 pipe to be turned, the movable jaw will drop into engagement with the upper side of the pipe and due to the angular relation of the teeth 4 and 17, the pipe will be firmly gripped when the downward pressure is 45 exerted against the handle 1. It will further be seen that as the teeth 17 bite into the pipe to be turned, there is a tendency for the movable jaw 16 to be drawn forwardly, in the event of which it must approach the 50 jaw 3 so that the pipe is firmly gripped.

In order that the thin pipes to which the wrench is applied may not be crushed when gripped by the jaws, means is provided for limiting the movement of the jaw 16 toward 55 the jaw 3, and this means consists of a relatively long threaded stem 20 which is threaded through the movable jaw 16 and is adapted to bear at one end against the face of the shank 2 or jaw 3. At its other 60 end the stem is provided with a head 21 by means of which it may be turned and adjusted.

Having thus described the invention, what is claimed as new is:

1. In a wrench, a shank, a fixed jaw carried thereby, the shank being provided with a series of seats, a support slidably adjustable upon the shank and including cheek plates, pins connecting the said plates and arranged to rest in the said seats interchangeably, means for yieldably holding the support in position with its pins so seated, and a movable jaw mounted upon the support and movable toward and away from the fixed jaw. 75

2. In a wrench, a shank, a fixed jaw carried by the shank, a support including cheek plates connected in spaced relation and slidably mounted upon the shank, the shank being provided with a series of seats, a pin 80 extending between the cheek plates and arranged to rest interchangeably in the seats, whereby to hold the support at adjustment upon the shank, a spring upon the support bearing against that side of the shank opposite the side in which the said seats are provided, and a movable jaw carried by the support and movable toward and away from the fixed jaw. 85

3. In a wrench, a shank, a fixed jaw carried by the shank, a support including cheek plates connected in spaced relation and slidably mounted upon the shank, the shank being provided upon one side with a series of seats, pins extending transversely between and connecting the cheek plates and engaging interchangeably in the seats, links pivoted to the said pins and projecting beyond that side of the shank opposite the side in which the seats are formed, and a 100 jaw supported by the said links. 90

4. In a wrench, a shank, a fixed jaw carried by the shank, a support including cheek plates connected in spaced relation and slidably mounted upon the shank, the shank being provided upon one side with a series of seats, pins extending transversely between and connecting the cheek plates and engaging interchangeably in the seats, links pivoted to the said pins and projecting beyond that side of the shank opposite the side in which the seats are formed, a jaw supported by the said links, the fixed jaw being provided with a series of teeth, and a spring upon the said support having an end co-operating with said teeth the spring acting to hold the support with the said pins in engagement in the seats. 110

In testimony whereof I affix my signature in presence of two witnesses.
